UNITED STATES PATENT OFFICE.

JOHN LYNCH, OF NEW HAVEN, MICHIGAN.

SAFETY-GUARD FOR RAILROAD-FROGS.

SPECIFICATION forming part of Letters Patent No. 292,834, dated February 5, 1884.

Application filed June 27, 1883. (No model.)

To all whom it may concern:

Be it known that I, JOHN LYNCH, a citizen of the United States, residing at New Haven, in the county of Macomb and State of Michigan, have invented a new and Improved Safety-Guard for Railroad-Frogs, of which the following is a specification.

My invention relates to an improved means for filling the spaces between the frogs or switches and rails in yards or places where a great many frogs and switches are used in close contiguity; and the object of the same is to avoid accident and loss of life to railroad-employés by preventing the almost daily occurrence of men getting their feet fastened or hung in the frogs and losing their lives by trains passing over them before they can extricate themselves from their perilous position. Contrivances of various kinds for this purpose have been devised, and where such are made with yielding platforms they will not answer, I think, when put into practical use, as good a purpose as solid guard devices, on account of their liability of becoming clogged with ice, snow, or other obstacle, or of their springs getting disarranged so as not to allow the platforms to descend and rise freely, or of their rotting or becoming granulated, as in cases when they are made of india-rubber—a material which has its character or condition very materially changed under the influences of very hot and very cold weather.

My invention consists in certain combinations of solid guard-blocks of peculiar construction with the main rails, check-rails, and frog or switch rails, as will be hereinafter described and specifically claimed.

In the accompanying drawings, Figure 1 is a plan view of the frog-section of a railroad-track having my improved guards applied to it. Figs. 2 and 3 are detail perspective views of two angular or flanged guard-blocks used in forming my safety-guard. Fig. 4 is a vertical longitudinal section in the line $x-x$ of Fig. 1. Fig. 5 is a transverse vertical section in the line $y-y$ of Fig. 1. Fig. 6 is a vertical longitudinal section in the line $z-z$ of Fig. 1; and Fig. 7 is a plan view similar to Fig. 1, but illustrating more fully the construction of a railroad-track at the frog and switch section.

In the drawings, A A represent the rails of the main track; B B, the rails of the side

track, and C C the check-rails, the check-rails having a length about nine feet.

D D are solid rigid safety-guards, of either wood or metal, shaped to fit the inner sides of the rails A and C and C and B, and arranged between the same, as shown. Each of these guards is formed of two blocks, d, of equal size, made of either wood or metal, the end of one block abutting against a like end of the other at a point midway of the length of a check-rail, C, and each of the said blocks is provided with a hooking beveled flange, d', at its outer end, and with a channel, d'', on its top, as shown plainly in Fig. 2 of the drawings. The flanges on the ends of the blocks d d hook against the ends of the check-rails, and through their beveled surfaced portions spikes d''' are passed down into holdfasts or cross-ties of the road, 7c for the purpose of confining them permanently, abutting against each other at d' and against the check-rails. The flanges d' prevent longitudinal movement of the guard-blocks from each other when a train is passing over the frog-section of the track, while their channels d'' afford room for the flanges of the car and engine wheels. The guards D D are designed for filling the spaces between the check-rails C and the rails A C and B C to about the extent of 80 the entire length of the check-rails, and to form a solid footing for pedestrians crossing the frog-section of the railroad-track. The manner of constructing the guards D D of solid and rigid material, either wood or metal, 85 and of securing them in position, constitutes the main novelty of this part of my invention.

E E are safety-guard blocks at those ends of a main rail, A, and a branch rail, B, which terminate at the frog F. These guard-blocks 90 are formed of either metal or wood, with a flange, e, and a beveled spiking - surface, through which spikes e' are driven into a cross-tie of the railroad. The top surfaces of these blocks are grooved at g', and lie on a 95 plane below the said rails A and B. One of these guard-blocks is placed between the terminating end of a branch rail, B, and the frog-point f, and another between the terminating end of a main rail and said frog-point, as 100 shown, the flanges e of said guard-blocks bearing, respectively, against the terminating ends of the said main and branch rails A and B. The guard-blocks thus placed serve to fill the

spaces between the frog and the terminating ends of said rails, and thereby form a solid rigid footing for pedestrians crossing over the track where they are placed.

5 G is a doubly-flared safety-guard block, also placed between the inner main and inner branch or side track rail. This guard is set in position before the said rails A and B are spiked down, and it abuts at g^2 against the 10 guard-blocks E E, as shown. This guard-block G is formed, either of metal or wood, with a flare at each end. In one of the flared ends a notch, g^4 , is provided, so that it may be fitted to the point f^5 of the frog F. On its 15 sides it is bulged so as to fit the sides of the rails A and B, and on its top it is grooved, as at g^4 , to afford room below the top of said rails for the flanges of the wheels of the cars and engine while a train is moving over the frog-section of the track. Through the other flared end, e , of the guard G, which is beveled, a spike, e' , is driven down into a sleeper for the 20 purpose of holding it firmly in position, abutting, as at g^2 , against the blocks E E, while a 25 train is passing over the frog-section of the track. The guard-blocks E E and G fill the dangerous spaces between the frog and the rails A and B, which unite with it; and by 30 reason of the doubly-flared form of the block G, longitudinal movement thereof, either backward or forward, is prevented, while by the flanges e , formed on the blocks E, and the spikes e' , these latter blocks are kept with an 35 abutting contact at g^2 against the block G, and cannot move longitudinally while a train is 40 passing over the frog-section of the track. The guard-block G is made of such length as will make the space at the frog-section of the track safe to walk over, or so as to have said 45 block about five to eight inches wide at its broadest end. The construction of the guard-blocks of solid rigid material, and the mode of applying the guard-blocks E and G, as herein shown and described, constitutes the main novelty of this part of my invention.

H is a V-shaped guard-block placed in the frog proper. For the reception of this guard-block the space between the frog-rails A and B is shaped to form a sort of socket or recess,

f^6 , into which the tapered point f^5 of the block 50 passes, as illustrated in Fig. 4. The block H is shaped on its sides to conform to the said frog-rails, to overhang the same slightly, and have its top surface about on a level with the 55 top of the same, as shown. At the outer or broadest end of the block H a flange, h^2 , is provided, and through this flange a spike, h^3 , is driven into a cross-tie of the road, for the purpose of fastening said block in position. This guard-block H fills the space between the 60 frog-rails, and makes it safe for pedestrians crossing the frog-section of the track, and its length will be such as to have its widest or flared end of a width, say, from five to eight 65 inches.

I do not claim india-rubber or other yielding platforms, or cushions placed between rails for the purpose of forming a safety-guard at the frog-section of a railroad-track, unless my special construction of the guards is 70 adopted in connection with the use of such material; but

What I do claim is—

1. The combination of the divided flanged guard D with a main rail, A, and check-rail C, substantially as and for the purpose described. 75
2. The combination of the divided flanged guard D with a branch or side track rail B, and a check-rail, C, substantially as described. 80
3. The combination of the flanged guard-blocks E and the doubly-flared guard-block G with the frog F, and the rails A and B, substantially as and for the purpose described. 85
4. The solid rigid V-shaped guard H, beveled at h^2 , provided with a spike-hole at h^3 , and formed with a point, f^5 , in combination with the frog F and rails A and B, substantially as and for the purpose described. 90
5. The frog-section of a railroad-track, provided with the rigid divided guards D D G E, and the rigid guard H, all constructed, combined, and arranged substantially as described.

JOHN LYNCH.
